CONSTRUCTION OF VENETIAN BLINDS

Walter Turkowski, Hellywood, Ill., assignor to Walter Turkowski and Bernice Turkowski, Hellywood, Ill.

Application May 25, 1951, Serial No. 228,161

6 Claims. (Cl. 160—118)

My invention relates to adjustable window blinds of the type commonly known as Venetian blinds.

My invention relates more particularly to Venetian blinds of the type that are adapted to be suspended vertically rather than the usual horizontal position.

The principal object of the present invention is to provide universally adjustable Venetian blinds of the type which may be vertically suspended in a window, may be opened or closed, partially opened or closed, draped from the top towards both sides of the bottom of the window, or as a body slid to the side of the window so that there is no apparent blind of any kind in front of the window.

Heretofore applicant has provided various constructions of vertical Venetian blinds, blinds which have included adjustments whereby they may be turned about a vertical axis to control the amount and direction of light and air, or may be gathered or draped at the lower end.

The present invention goes one step further in that it now provides mechanism for moving a plurality of normally vertically disposed slats or shutters sideways to permit disclosing practically the entire window and presenting the effect of having no blinds whatsoever hanging in front of the same.

A further object of the invention is to provide multiply adjustable vertical Venetian blinds which include two sets of equally spaced vertically disposed blinds mounted in a unitary frame adapted to be hung in the window frame.

A further object of the invention is to provide an improved multiply adjustable vertical Venetian blind which includes a pair of sets of vertically disposed slats or shutters and identical mechanism associated with each for controlling both the location and position of its particular set of slats, both sets being mounted in a unitary frame capable of being suspended in a window frame.

Other objects and advantages will be more apparent from the following description wherein reference is had to the accompanying sheets of drawings, upon which

Fig. 1 is a front elevational view showing one of the multiply adjustable vertical Venetian blind units mounted in position in a window frame;

Fig. 2 is a vertical sectional view thereof taken on the line 2—2 of Fig. 1;

Fig. 3 is a side elevational view of the parts shown in Fig. 2 with portions broken away to more clearly show other parts;

Fig. 4 is a plan sectional view taken on the line 4—4 of Fig. 2;

Fig. 5 is a fragmentary side elevational view of the parts shown in Fig. 4;

Fig. 6 to Fig. 13 inclusive are generally diagrammatic views showing the various combinations or window effects which may be accomplished by employing the construction which I provide, and are described as follows:

In Fig. 6 both sets of shutters are in their vertical open position;

In Fig. 7 both sets of shutters are closed to exclude air and light;

5

Fig. 8 shows both sets of shutters as draped toward the bottom;

In Fig. 9 both sets of shutters are pushed to the side as far as possible, generally exposing most of the window surface to direct air and light;

In Fig. 10 the left shutter is swung to the left as far as possible to permit air and light to enter, and the right shutter is hung in the normal vertical position;

In Fig. 11 the left shutter is shown with the vertical slats turned about their axis to completely shut out air and light, and the right shutter is moved entirely to the right side, exposing the entire right half of the window to air and light;

In Fig. 12 the left shutter is completely collapsed against the left side of the frame, and the right shutter is shown in a draped position; and

In Fig. 13 the left shutter is draped toward the bottom and the right shutter is hung vertically suspended permitting air and light to enter.

20 In the embodiment of the invention which I have chosen to illustrate and describe the same, in Fig. 1 I have shown a Venetian blind unit which employs two sets of adjustable vertically disposed slat members, the unit comprising a U-shaped frame including the two side frame members 16 and 18 connected to the top cross-frame member 20. The top cross-frame member may have a rod 22 extending through the end walls 24 and 26 of the same, the rod acting as a support for the entire unit and being supported at its ends upon suitable bracket members 28 fastened to the side walls of the window frame 30, each of the brackets 28 having an open-ended slot 32 whereby the rod 22 can be inserted from the top and permitted to settle in the slots 32.

25 The lower ends of the side frame members 16 and 18 may be suitably fastened to the vertical walls of the window sill 30 by means of screw members 34 which extend through slots 36 in the frame and into the side of the window frames. As previously mentioned, a pair of groups of vertically disposed slats may be hung in each of 30 the window blind units, each set of slats S including top and bottom control members 40, best shown as units in Figs. 4 and 5.

35 Each of the control members or assemblies may include a pair of spaced parallel arm members 42 and 44 connected at one end by a pivoted lever 46 and at their extended ends by a slat yoke 48.

40 Each of the pivoted levers 46 is adapted to be mounted on a side bracket 50, the brackets having a vertical wall 52 aligned with the inside of the side frame members 16 and 18, being fastened thereto by a screw member 53 that extends through the vertical slot 36 previously mentioned. Each of the brackets 50 also has a forwardly extending handle portion 54 capable of manual manipulation to raise and lower the assemblies 40, as will be hereinafter described.

45 The control members 40 associated with each set of vertical slats, may be fastened together by a vertical rod member 56 securely fastened to the upper side bracket 50 and extend through a slot 58 in the lower side bracket 50, the lower end of the rod having a pivoted wing portion 60 connected thereto so that when the wing is turned at right angles it may be passed through the elongated slot 62 in the lower bracket 50 to disconnect the same. This is necessary for certain adjustments which will be later described.

50 The control members 40 may have a plurality of yoke members 48 connected between the side arms 42 and 44 of the same by means of bolt members 66 which pass through openings in the sides of the arm members 42 and 44 and receive a cotter pin 68 which is dropped through a pair of arm members 70 on the sides of the yokes 48. Each of the yokes is provided with an arcuately shaped

slot 72 through which a vertically disposed slat S may be passed so that when the control member 40 is turned as a unit about the pivot lever 46, the slats will all be turned at the same angle and in spaced parallel position. The end yoke 48 is preferably rigidly connected by means of pin members 80 to the end slat S so that while the opposite ends of the control members may be raised or lowered, the end yoke 48 and the ends of the control member are always fixedly connected at this point to the end slat S.

With the construction I have thus provided a number of possibilities are readily apparent. In the first place, it is obvious that the entire frame member or unit is capable of being lifted off of the support brackets 28 for washing, repair or replacement.

By referring to Figs. 6 to 13, it can be seen that a number of interesting and desirable adjustments can be made. For example, in Fig. 6, the Venetian blind assembly is shown with all of the slats S vertically disposed from the rod 22 to permit the maximum of daylight to be introduced through the window frame. By moving each of the control members 40 sideways, the slats S are rotated about their vertical axis sufficiently to effect a complete closure of the space in the window frame. This may be done by reason of the fact that each of the slats is provided with the elongated slot 91 so that it can hang from the cross-rod 22, be angularly moved thereon, or rotated through a large radius on the same.

In Fig. 8 I have shown both of the lower control members 40 loosened from the vertical rod 56 and moved downwardly so that a drape effect is provided by each set of vertical slats. In Fig. 9 I have shown the slats gathered adjacent the sides of the window. This is done by moving downwardly the outer sides of the control members 40 as a unit connected together by the vertical rod 56. In this manner the maximum amount of light can be secured through the window opening 30.

In Fig. 10 I have shown another adjustment which is possible with the construction I have provided. In this adjustment the side assembly 93 is closed against the left window frame wall and the right assembly 95 is shown with the slats in the vertical position to permit light and air to pass between the same.

In Figs. 11, 12 and 13 I have shown the other adjustments in which the unit may be placed, Fig. 11 showing generally half of the window closed and half open, Fig. 12 showing half of the window open and the other side draped, and Fig. 13 showing one unit with the slats hanging in a vertical position and the other unit with the slats draped.

It can thus be seen from the variety of adjustments provided that the unit is capable of practically universal adjustment and the amount of air and light which it is desired to secure can be controlled in a variety of ways. The window closure is thus capable of a variety of effects which are not possible with any other type of Venetian blinds, drapes or window shades.

While I have illustrated and described a specific embodiment of the invention, it will be apparent to those skilled in the art that changes and modifications may be made in the exact details shown and I do not wish to be limited in any particular; rather what I desire to secure and protect by Letters Patent of the United States is:

1. A window blind for mounting in a rectangular window frame including a U-shaped frame having a horizontal top cross frame member and vertical side frame members, a rod in said top cross-frame member having its ends extending beyond both ends of said top cross-frame member and adapted to support said window blind on brackets in said window frame, a plurality of vertically positioned slats, each having means for supporting said slats on said rod for sliding movement longitudinally of said rod and for pivotal movement of said slats on their individual axes, and means for imparting sliding movement to said slats to gather the same together adjacent

a side frame member, turning the same about their longitudinal axes, or draping the same adjacent their lower ends, said means including a control member having arms on two sides of said slats, yoke members pivotally connected between said arms, said slats extended through said yokes, a lever connected to a side frame member, said arms pivotally connected to said lever and said lever vertically slidably mounted in said side frame member.

10 2. A window blind for mounting in a rectangular window frame including a U-shaped frame having a horizontal top cross frame member and vertical side frame members, a rod in said top cross-frame member having its ends extending beyond both ends of said top cross-frame member and adapted to support said window blind on brackets in said window frame, a plurality of vertically positioned slats, each having means for supporting said slats on said rod for sliding movement longitudinally of said rod and for pivotal movement of said slats on their individual axes, and means for imparting sliding movement to said slats to gather the same together adjacent a side frame member, turning the same about their longitudinal axes, or draping the same adjacent their lower ends, said means including a control member having arms on two sides of said slats, yoke members pivotally connected between said arms, said slats extended through said yokes, a lever connected to a side frame member, said arms pivotally connected to said lever and said lever vertically slidably mounted in said side frame member, said arms also pivotally connected to the end slat from the side frame member.

3. A window blind for mounting in a rectangular window frame including a U-shaped frame having a horizontal top cross frame member and vertical side frame members, a rod in said top cross-frame member having its ends extending beyond both ends of said top cross-frame member and adapted to support said window blind on brackets in said window frame, a pair of sets of vertically positioned slats, each slat in each set having means for supporting said slat on said rod for sliding movement longitudinally of said rod and for pivotal movement of said slats on their individual axes, and means for imparting sliding movement to said slats to gather the same together adjacent a side frame member, turning the same about their longitudinal axes, or draping the same adjacent their lower ends, said means including two sets of control members, each set having arms on two sides of said slats, yoke members pivotally connected between said arms, a set of said slats extended through said yokes, a lever for each set of slats, one connected to each of said side frame members, said arms pivotally connected to said lever and said lever vertically slidably mounted in said side frame member.

4. A window blind for mounting in a rectangular window frame including a U-shaped frame having a horizontal top cross frame member and vertical side frame members, a rod in said top cross-frame member having its ends extending beyond both ends of said top cross-frame member and adapted to support said window blind on brackets in said window frame, a pair of sets of vertically positioned slats, each slat in each set having means for supporting said slat on said rod for sliding movement longitudinally of said rod and for pivotal movement of said slats on their individual axes, and means for imparting sliding movement to said slats to gather the same together adjacent a side frame member, turning the same about their longitudinal axes, or draping the same adjacent their lower ends, said means including two sets of control members, each set having arms on two sides of said slats, yoke members pivotally connected between said arms, a set of said slats extended through said yokes, a lever for each set of slats, one connected to each of said side frame members, said arms pivotally connected to said lever and said lever vertically slidably mounted in said side frame member, said arms also pivotally con-

nected to the end slats from the side frame members whereby when either of the control members is operated the set of slats controlled thereby can be turned on its longitudinal axis, moved in a group toward a side frame member or draped adjacent their lower ends.

5. A window blind for mounting in a rectangular window frame including a U-shaped frame having a horizontal top cross frame member and vertical side frame members, a rod in said top cross-frame member having its ends extending beyond both ends of said top cross-frame member and adapted to support said window blind on brackets in said window frame, a plurality of vertically positioned slats, each having means for supporting said slat on said rod for sliding movement longitudinally of said rod and for pivotal movement of said slats on their individual axes, and means for imparting sliding movement to said slats to gather the same together adjacent a side frame member or turning the same about their longitudinal axes, said means including a pair of control members one located near said top cross-frame member and one located about medially of the length of said slats, each control member having a pair of arms one on each side of said slats, yoke members pivotally connected between said pair of arms, said slats extended through said yokes, the end slat from the side frame member being pivotally connected to its yoke and each control member having a lever connected to a side frame member, each of said pair of arms pivotally connected to one of said levers and said levers vertically slidably mounted in said side frame member.

6. A window blind for mounting in a rectangular window frame including a U-shaped frame having a horizontal top cross frame member and vertical side frame mem-

bers, a rod in said top cross-frame member having its ends extending beyond both ends of said top cross-frame member and adapted to support said window blind on brackets in said window frame, a plurality of vertically positioned slats, each having means for supporting said slat on said rod for sliding movement longitudinally of said rod and for pivotal movement of said slats on their individual axes, and means for imparting sliding movement to said slats to gather the same together adjacent a side frame member or turning the same about their longitudinal axes, said means including a pair of control members one located near said top cross-frame member and one located about medially of the length of said slats, each control member having a pair of arms one on each side of said slats, yoke members pivotally connected between said pair of arms, said slats extended through said yokes, the end slat from the side frame member being pivotally connected to its yoke and each control member having a lever connected to a side frame member, each of said pair of arms pivotally connected to one of said levers and said levers vertically slidably mounted in said side frame member, said levers having a rod rigidly connected between the same whereby movement of one in a vertical direction will move the other.
